UNITED STATES PATENT OFFICE.

RUDOLF E. HELLMUND, OF SWISSVALE, PENNSYLVANIA, ASSIGNOR TO WESTINGHOUSE ELECTRIC & MANUFACTURING COMPANY, A CORPORATION OF PENNSYLVANIA.

HIGH-VOLTAGE DIRECT-CURRENT SYSTEM.

1,396,839.

Specification of Letters Patent.

Patented Nov. 15, 1921.

Application filed September 10, 1917. Serial No. 190,503.

To all whom it may concern:

Be it known that I, RUDOLF E. HELLMUND, a citizen of the German Empire, and a resident of Swissvale, in the county of Allegheny and State of Pennsylvania, have invented a new and useful Improvement in High-Voltage Direct-Current Systems, of which the following is a specification.

My invention relates to high-voltage, direct-current systems, and particularly to the inherent overload protection of power-station or substation generators for supplying voltage to the operating circuits of a high-voltage railway system.

In the operation of high-voltage, direct-current railway systems; for example, 3000-volt systems, considerable difficulty has been encountered in preventing station generators from "flashing over", in the event of short circuits upon the railway system. As is well known, the circuit breakers commercially available, although operating to open a circuit in a very small fraction of time, nevertheless permit the short-circuit current to instantaneously rise to a dangerous value. Consequently, further protection, preferably of an inherent character, is desirable, if not necessary, for satisfactory operation of the station generators.

The object of my present invention, therefore, is to provide a relatively simple system of the above-indicated character, whereby the instantaneous rise of short-circuit current is sufficiently delayed by the inherent characteristics of the generator system to permit the circuit-breaker to open the generator circuit before dangerously high currents are attained.

My invention may best be understood by reference to the accompanying drawings, wherein Figure 1 is a diagrammatic view of the component elements, namely, station generating apparatus and railway rolling stock, of a high-voltage direct-current railway system embodying the invention; Fig. 2 is a diagrammatic view of a modified form of generator system constructed and arranged in accordance with the invention; Fig. 3 is a sequence chart of well-known form, indicating the preferred order of operation of the switches that are shown in Fig. 2; Fig. 4 and Fig. 5, Fig. 6 and Fig. 7, Fig. 8 and Fig. 9, are views, respectively corre-

sponding to Fig. 2 and Fig. 3, of further modifications of my invention.

Referring to Fig. 1 of the drawings, the system shown comprises supply-circuit conductors Trolley and Ground; a power-station or substation direct-current generator having an armature A and an exciting field winding F; a driving induction motor M for the direct-current generator; an auxiliary exciter 5 that is also driven by the motor M; a transformer 6 that is associated with the various machine circuits in a manner to be set forth; a variable resistor 7 for adjusting the exciting circuits, and a railway vehicle 8 that operates in the customary manner, receiving energy from the trolley and returning it through the rails to ground.

It will be understood that, in lieu of the driving induction motor M, any suitable type of prime mover, such as a steam turbine or a gasoline-engine, may be employed, if desired.

The exciter 5 comprises a commutator-type armature 15, which is mounted upon the operating shaft 16 of the main motor generator set, and a series-related field winding 17.

The transformer 6 comprises a winding 18 having a relatively large number of turns and a second winding 19 having a smaller number of turns, both of the windings being disposed, in any suitable manner, upon a common core member 20.

As is customary station practice, a suitable circuit-breaker is connected in series relation with the main generator armature A to interrupt the generator circuit under overload conditions. Since the particular type of circuit-breaker that is employed is immaterial to my present invention, I have not deemed it necessary to illustrate any circuit-breaker in detail, but have merely shown the trip-coil and contact members, which are labeled "Circuit breaker".

Under normal operating conditions, the main generator current, indicated by the solid arrows, is established from the ground through transformer winding 19, main armature A and the circuit-breaker trip-coil and contact members to the trolley. The auxiliary exciting circuit, indicated by the dotted arrows, is established from the positive terminal of the exciter armature 15 through

2
the few-turn transformer winding 19, main field winding F, variable resistor 7 and parallel-related auxiliary field winding 17 and many-turn transformer winding 18, to the negative terminal of the exciter armature. If desired, the equivalent connection of the many-turn transformer winding 18 across the main field winding F may be employed.

The few-turn transformer winding 19 thus carries both the main-armature current and the exciting current in the same direction, while the many-turn transformer winding 18 carries only a portion of the exciting-armature current in the opposite direction to the current through the other transformer winding 19. Since the winding 18 has a relatively large number of turns, this winding predominates, and, under normal operating conditions, the transformer core 20 is highly saturated, so that slight changes of generator current or slight voltage fluctuations produce a substantially negligible effect in the transformer 6. The few-turn transformer winding 19, furthermore, inherently operates to maintain a substantially constant generated current in the main armature A, for the following reasons. Upon an incipient rise of such current, a correspondingly increased voltage drop obtains across the transformer winding 19, since both the main current and the exciting current traverse the winding in the same direction. Consequently, a decreased voltage is available for delivery to the main field winding F from the exciter armature 15, whereby the main-armature current is inherently caused to subside to its average value. The converse action takes place in the event of an incipient decrease of generated current, as will be understood.

In addition, under short-circuit conditions upon the railway system, or other conditions involving a dangerously heavy surge of generator current, the transformer 6 inherently acts to delay the rise of short-circuit current until the station circuit-breaker can open the generator circuit and thus eliminate the short-circuit conditions.

The additional inherent transformer action just mentioned may be explained as follows: upon the incipient rise of short-circuit current, the total transformer flux is materially diminished by reason of the traversal of the main-generator current through the transformer winding 19 differentially to the current in the normally predominating many-turn winding 18, and a certain opposing voltage is induced, under such abnormal conditions, across the many-turn transformer winding 18. In this way, by reason of the inherent tendency of the winding 19 to maintain its former energization, a material value of current is drawn from the auxiliary field winding 17 into the transformer winding 18, thus reducing the

voltage of the exciter and, therefore, the excitation of the main field winding F to correspondingly decrease the voltage of the main armature A. By reason of the inherent action just recited, therefore, the rise of short-circuit current is sufficiently retarded to permit the circuit-breaker to open the generator circuit before dangerously high currents are reached.

The normal starting operation of the illustrated motor-generator set requires but a brief description. The induction motor M may be started in any familiar manner to drive the main armature A and the exciter armature 15, the voltage of which rapidly builds up by reason of the illustrated closed-circuit connections through the field winding 17. The voltage of the main armature A may be varied by the station operator in any suitable manner; for example, by manipulating the illustrated resistor 7.

Referring now to Fig. 2, the system shown comprises the supply-circuit conductors trolley and ground; the driving induction motor M and the main station generator 90 with its related circuit breaker, as illustrated in Fig. 1; and, in addition, a motor-generator set 25 for exciting purposes; an auxiliary source of energy, such as a battery B; a plurality of variable resistors R, R₁ 95 and R₂, for purposes to be set forth; and a plurality of electrically-controlled switches 1, 2, 3 and 4.

The motor-generator set 25 comprises a driving or motor armature 27, which is coupled by means of a shaft 28, for example, to a generator or exciting armature 29. A series-related field winding 30; a shunt-field winding 31, which may be varied through the agency of the resistor R₂; and a commutating and neutralizing field winding 32 are provided for the auxiliary driving armature 27, while the generator armature 29 has an exciting field winding 33 that is energized in accordance with the load of the motor-generator set, and a commutating-field winding 34. Under normal operating conditions, the energization of the auxiliary field winding 33 in Fig. 2; Fig. 4, Fig. 6 and Fig. 8 is sufficiently great to highly saturate the corresponding magnetic circuit (not shown). Consequently, ordinary current or voltage fluctuations have practically no effect upon the flux corresponding to the field winding 33, which is thus operative for current-limiting purposes only under abnormal overload conditions, as hereinafter fully set forth.

The main generator armature A is connected, through the circuit-breaker, across the supply circuit, while the auxiliary generator armature 29 is connected, through the switch 3 and variable resistor R, across the main field winding F. As previously stated, the field winding 33 for the auxiliary gener-

ator armature is connected in series relation with the auxiliary-motor circuits, connection being completed to the respective supply-circuit conductors Trolley and Ground, 5 through switch 1 and variable resistor R1.

Assuming that the induction motor M is driving the main generator at normal speed, and that it is desired to supply voltage to the trolley circuit, the switches 2 and 4 are 10 first closed, as indicated in step *a* of the sequence chart, Fig. 3, to connect the battery B through the variable resistor R across the main-field winding F, and to initially short-circuit the auxiliary field

15 winding 30. By suitably adjusting the resistor R, the voltage of the main armature A may be increased to the desired operating value.

Switch 1 may then be closed to start the 20 motor-generator set, after the supply-circuit voltage has thus been established, and, by suitable regulation of the resistors R1 and R2 and by opening switch 4 to include the auxiliary field winding 30 in circuit, the 25 voltage of the auxiliary generator armature 29 may be increased to a value equivalent to that of the battery B, whereupon the switch 3 may be closed and the switch 2 opened 30 to disconnect the battery and permit subsequent energization of the main generator from the motor-generator set alone.

Assuming short-circuit conditions in the railway system after the generator system is normally operating, the voltage of the 35 main generator A instantaneously decreases materially, in accordance with familiar principles, whereby the simultaneous voltage of the auxiliary driving armature 27 is instantaneously held at a value greater than 40 that of the supply-circuit voltage, which causes a rapid reduction of the current in that armature and in the series-related field winding 33 for the auxiliary generator armature, by reason of the materially differ-

45 ent-from-normal relation of the supply-circuit voltage and the counter-electromotive force of the auxiliary driving armature. The action just recited is aided by the damping effect of the shunt field winding 31 for the auxiliary driving motor. Since the 50 speed of the armature 27 is only slightly affected by changes of supply-circuit voltage, by reason of such shunt excitation, under the short-circuit conditions in question and the consequent instantaneous drop 55 of supply-circuit voltage, the damping effect of the shunt field winding 31 tends to maintain a relatively high counter-electromotive force in the armature 27 to effect the desired

60 inherent regulation. The voltage of the auxiliary generator armature 29 is thus quickly diminished to correspondingly reduce the excitation of the main-field winding F. In this way, the generator voltage 65 of the main armature A is further decreased

to retard the rise of short-circuit current and permit the circuit-breaker to open the generator circuit before dangerous current conditions have been attained.

Reference may now be had to Fig. 4, 70 wherein the system shown comprises supply-circuit conductors and a main motor-generator set similar to those illustrated in Fig. 3, and, in addition, an auxiliary motor-generator set 40, a battery B1 for exciting one of 75 the field windings thereof, variable resistors R and R1, and an inductive device 41.

The auxiliary motor-generator set is driven by, or mechanically coupled to, the main set in any suitable manner, a belt drive 80 42 being indicated for the sake of simplicity and clearness. Under operating conditions, however, the auxiliary set functions electrically in a manner similar to a mechanically independent set. 85

Electrically, the motor-generator set 40, in general, is similar to the previously-described set 25, the chief difference residing in the connection of the battery B1 through the switch 1, across the field winding 33 for 90 the auxiliary generating armature 29, which field winding is normally energized in accordance with the load-current of the motor-generator set 40. Furthermore, a shunt-field winding 44 for the auxiliary driving armature 27 is connected through switch 3, to one terminal of the commutating field winding 32 and through variable resistor R1, switch 2, and variable resistor R, to the lower terminal of the auxiliary motor armature. 100

By reason of connecting the battery B1 across the auxiliary field winding 33, a materially smaller-capacity battery may be utilized than is necessary in the system 105 shown in Fig. 2, wherein the storage battery is employed to energize the main-field winding F.

The inductive device 41 may be of any well-known type and is employed for the 110 customary purpose of limiting or choking down sudden variations of current in the circuits wherein it is connected. When traversed by both the main-armature current and the exciting current, a double current-limiting function is performed by the inductive device, which also acts, in a similar manner to the transformer winding 19 of Fig. 1, to inherently prevent current changes. 115

In the present case, the main-armature circuit, indicated by the solid arrows, is established from the ground through the inductive device 41, the main armature A and the circuit-breaker to the trolley. 120

The exciting or main-field winding circuit, indicated by the dotted arrows, is established from the positive terminal of the generator armature 29, through the inductive device 41, main-field winding F, and 130

commutating field winding 34, to the negative terminal of the generator armature 29.

As indicated in the sequence chart, Fig. 5, switch 1 is initially closed after the two 5, motor-generator sets are operating at normal-speed conditions, whereby the voltage of the auxiliary generator armature 29 is quickly built up to the desired value in accordance with the adjustment of the re- 10 sistor R.

The second step of the control involves the closure of switch 3 to include the field winding 44 for the auxiliary driving armature 27 in circuit.

15 As soon as the exciting system conditions have become stable, the switch 2 may be closed and the switch 1 may be opened, as indicated in the sequence chart, to connect the motor armature 27 in circuit and to 20 disconnect the battery B1 to effect the normal excitation of the main generator from the auxiliary motor-generator set alone.

The inherent operation of the illustrated system to retard the rise of short-circuit current is substantially identical with the 25 operation set forth in connection with Fig. 2, by reason of the connection of the field winding 33 for the auxiliary generator armature 29 in series relation with the auxiliary motor armature 27. Consequently, no 30 further exposition of such inherent action is deemed necessary.

The system of Fig. 6 differs from that shown in Fig. 4 chiefly in the entire omission of storage batteries, and also in the connection of a shunt field winding 46 for the auxiliary driving armature 27, through a variable resistor R2 across that armature and another variable resistor R1, and in the 40 connection of the variable resistor R through switch 1 across the entire auxiliary generating machine, comprising armature 29 and field windings 34 and 33.

By reference to the sequence chart, Fig. 45 7, it will be seen that switch 1 is initially closed after the motor-generator sets are running, whereby the voltage of the auxiliary generator armature 29 rapidly builds up by reason of the local exciting circuit 50 including switch 1, variable resistor R and field windings 33 and 34.

In the second step of the control, switch 3 is closed to energize the main-field winding F. As soon as stable excitation conditions obtain in the system, switch 2 may be next closed and switch 1 may be opened, as indicated in step c of the sequence chart, to permit the full auxiliary-motor current to traverse the field winding 33 for the generator armature 29; further regulation, if necessary, being accomplished by suitable manipulation of the resistors R1 and R2.

Inasmuch as the inherent action of the exciter system, to prevent a dangerous rise 65 of overload main-generator current, is simi-

lar to that set forth in connection with Fig. 2, no further description of such operation is considered necessary.

In Fig. 8, the shaft 16 of the main motor-generator set carries, in addition to the driving induction-motor rotor and the main-generator armature A, an auxiliary machine 50, which is employed for starting purposes, to be set forth.

70 An auxiliary motor-generator set 51, comprising armatures 27 and 29 and field windings 33 and 44, is utilized for separately exciting the main-field winding F, variable resistors R1 and R2 being connected in series-circuit relation with the auxiliary field 80 windings 33 and 44, respectively.

The auxiliary machine 50 comprises a commutator-type armature 55, which is driven by the induction motor M, and a field winding 56, which is connected through 85 switch 4 and variable resistor R across the supply circuit. The induction device 41 and a fixed resistor 52 are connected in series-circuit relation with the auxiliary armature 55, which may likewise be connected to 90 the supply-circuit conductor Trolley by switch 4, the provision of such impedance devices effectively preventing dangerous current conditions in the auxiliary armature 55, at any time.

95 As indicated in the sequence chart, Fig. 9, switch 4 is closed, after the main motor-generator set is running, to establish a supply-circuit voltage from the auxiliary machine 50, which voltage may be set at any 100 particular value by suitable manipulation of the resistor R.

Switches 2 and 3 are then closed to connect the auxiliary driving motor 27 and the series-related field winding 33 for the generator armature 29 across the energized supply circuit, whereby the voltage of the main-field winding F may be increased to any desired value by adjusting the resistors R1 and R2.

110 After stable excitation conditions obtain, switch 1 may be closed to connect the main generator armature A, through the circuit breaker, to the supply circuit, and, if desired, switch 4 may then be opened to allow 115 the auxiliary machine 50 to run idle, or the machine 50 may be utilized to supply a portion of the necessary energy to the high-voltage railway system.

120 As hereinbefore mentioned, the auxiliary machine 50 is protected against short-circuit conditions through the agency of the impedance devices 41 and 52, while dangerous increases of main generator current are again prevented through the previously-described inherent action of the field winding 33 for the auxiliary generator armature 29, which field winding is connected in series 125 relation with the auxiliary driving motor.

I do not wish to be restricted to the spe- 130

cific circuit connections or arrangement of parts herein set forth, as various further modifications thereof may be effected without departing from the spirit and scope of my invention. I desire, therefore, that only such limitations shall be imposed as are indicated in the appended claims.

I claim as my invention:

1. In a system of distribution, the combination with a direct-current generator, of an auxiliary exciting system therefor, an inductive means in said system for inherently counteracting overload generator currents of large amplitude to a greater extent than upon smaller load increments.

2. In a system of distribution, the combination with a direct-current generator, of an auxiliary exciting system therefor, and inductive means inherently active only under predetermined abnormal conditions for retarding the rise of generator current.

3. In a system of distribution, the combination with a main direct-current generator, of an auxiliary generator for exciting the main generator, and means dependent upon the inherent action of the auxiliary generator circuits for retarding the rise of main-generator current under predetermined abnormal overload conditions only.

4. In a system of distribution, the combination with a main direct-current generator, of an auxiliary generator for exciting the main generator, and a motor for driving said auxiliary generator, said auxiliary generator having a field winding energized in accordance with the load current of said motor to normally produce magnetic saturation conditions.

5. In a system of distribution, the combination with a main direct-current generator, of an auxiliary generator for exciting the main generator, a motor for driving said auxiliary generator, said auxiliary generator having a field winding energized in

accordance with the load current of said motor to normally produce magnetic saturation conditions, and means for initially energizing the main generator field winding.

6. In a system of distribution, the combination with a main direct-current generator, of an auxiliary generator for exciting the main generator, a motor for driving said auxiliary generator, said auxiliary generator having a field winding energized in accordance with the load current of said motor to normally produce magnetic saturation conditions, and means for initially energizing said auxiliary generator field winding.

7. In a system of distribution, the combination with a main direct-current generator, of an auxiliary generator for exciting the main generator, a motor for driving said auxiliary generator, said auxiliary generator having a field winding energized in accordance with the load current of said motor to normally produce magnetic saturation conditions, and means for initially closing an auxiliary exciting circuit around said auxiliary generator.

8. In a system of distribution, the combination with a load circuit, of a main direct-current generator, an auxiliary direct-current generator, and a driving motor for said auxiliary generator, the field winding of said main generator being energized by said auxiliary generator, the field winding of said auxiliary generator being energized from said load circuit in series circuit with said driving motor, and said series circuit being so designed that the magnetic flux of said auxiliary generator is only slightly affected by slight voltage fluctuations of said load circuit but is materially decreased by an abnormal voltage drop in said load circuit.

In testimony whereof, I have hereunto subscribed my name this 30th day of August, 1917.

RUDOLF E. HELLMUND.
